United States Patent Office

Des. 188,197
Patented June 14, 1960

188,197

DRESSER

Ernest L. Swarts and Orville B. Solie, Rockford, Ill., assignors to The Lane Company, Inc., Altavista, Va., a corporation of Virginia

Filed June 24, 1959, Ser. No. 56,528

Term of patent 14 years

(Cl. D33—6)

The figure is a front perspective view of a dresser showing our design.

The side not shown is like the side shown while the back is conventionally plain.

We claim:

The ornamental design for a dresser, as shown and described.
